UNITED STATES PATENT OFFICE.

WILLIAM P. PATTON AND CHARLES D. WALTERS, OF HARRISBURG, PENN.
SYLVANIA, ASSIGNORS TO EBY BYERS & SON, OF SAME PLACE.

IMPROVEMENT IN DUMPING-WAGONS.

Specification forming part of Letters Patent No. 159,211, dated January 26, 1875; application filed December 26, 1874.

To all whom it may concern:

Be it known that we, WILLIAM P. PATTON and CHARLES D. WALTERS, of the city of Harrisburg, county of Dauphin and State of Pennsylvania, have invented a new and useful Improvement in Coal Carts or Wagons; and we do hereby declare the following to be a full, clear, and exact description of the same and its manner of operation, reference being made to the annexed drawings making a part of this specification and the letters of reference marked thereon.

In the drawings, Figure 1 represents a side elevation of a coal-cart constructed upon our improved plan. Fig. 2 is a plan view of the body of the cart with the wheels removed. Fig. 3 is a view of portions of the two sections of the folding chute, and shows their jointed connection and the locking-clamp that holds them in an extended position. Fig. 4 is a rear-end elevation of the cart-body. Fig. 5 is a side view of the rear end of the cart-body and a portion of the chute. Fig. 6 is a cross-section of the coal-conveying chute. Fig. 7 represents the outer end of the chute and its swivel or caster-wheel in position.

In all the figures like letters represent like parts.

The nature of our invention consists in the combination of an adjustable folding chute of peculiar construction with a cart-body that has its bottom side inclined or pitched from front to rear, and is provided with hinged or swinging gates at its rear end, and also is further provided with a longitudinal partition or division wall that separates the body into two equal receptacles, substantially as is herein-after set forth. Our invention further consists in the use of a peculiar locking-catch, in combination with the sections of the rule-jointed folding chute, substantially as is herein-after shown and described.

The cart-body A (see Fig. 1) is made of either wood or iron, and is of proper size to contain a ton of coal. It has its bottom side pitched or inclined from front to rear end, as is shown. It is mounted upon two wheels, B. These should be of proper strength and of such relative diameter as to elevate the body A a proper height. Said body is se-

curely attached to the axle, and is supported at its front end by the bolster b, that is framed into the shafts D, said shafts being rigidly fastened to the cart-axle. A longitudinal partition, E, divides the body A into two equal parts, as is shown in Fig. 2. At the rear end of the body A two doors or gates, e e, are hinged to a rod or bar, so that they will swing from their upper ends as a point of suspension. These gates may be either the full height of the rear end of the cart-body, or they may be hinged to a bar that is rigidly secured across the rear end a proper distance from the upper edge of the body A. In the latter case the gate F is hinged above the gates e e, so as to fold down upon them, as is shown in Fig. 5. The gates e e are secured in place by the cross-bars s s that are pivoted to them in such a manner as to permit vibration and allow their ends to catch in notches made for their reception, as shown at r, Fig. 5. The upper door or gate F (shown in Figs. 4 and 5) is provided to facilitate the loading of the cart. It can be secured in a closed position by latches or other proper device. Upon the rear end of the cart-body A a short trough or delivery-spout, C, is rigidly attached. It is made of sheet metal, and is given the form substantially as is shown in the different figures. As will be observed, it is made the full width of the cart-body at the point of junction therewith. The sides from that point are drawn in toward each other somewhat as the outer end is neared, as is shown in Fig. 2 at i i.

The chute or conveying-trough T is constructed of sheet metal of a proper thickness to secure rigidity. It is composed of two or more sections, c d. These are secured together by a rule-joint, as is shown in Fig. 3. By an inspection of said figure it will be seen that the end of section c is caused to project forward beneath the end of section d in such a manner as to act as a stop or abutment, and prevents the sections from being opened past the proper point, or when the bottoms of the sections are in a straight line with each other, thus forming a rule-joint connection between them. When the sections c d are opened out in a straight line they form a continuous conveying-trough, the

sides of which regularly diminish in width from each other, so that the outer end of the section *c*, that enters the cellar or vault-hole, will be of a proper width to permit its insertion therein. A caster-wheel, 6, (see Fig. 7,) is attached to the lower side of the outer end of section *c*, and is intended to assist the operation by supporting said end, and permitting it to move freely in any direction on the pavement. The bottoms of the sections *c d* are curved or rounded, as is shown by the cross-section of one in Fig. 6. The section *c* has a portion, *n*, that projects forward under the proximate end of section *d*. Said portion *n* has an enlargement formed upon the lower surface of its extremity that projects downward at a right angle to the same. A locking-clamp, *o*, is pivoted to turn upon a central bolt or rivet that holds it in position upon the lower side of the section *d*. (See Fig. 3.) Said locking-clamp *o* hooks over the projection on the end of section *c*, and so secures the two sections rigidly together in a line, when they are extended and the clamp *o* turned in the position shown in said Fig. 3. A similar clamp, *u*, is provided to secure the section *d* rigidly in a line with the lower side of the fixed trough *C*, said section being pivoted or bolted thereto, so as to permit it to be folded up, as is shown in Fig. 1, or extended in line with said spout, as is shown in Fig. 5. Both sections *c d* are folded together, as is shown in Fig. 1, and secured in position by a chain, 5, that extends around them from the sides of the cart-body, one end of the same being fastened to the cart-body frame, the other passing over a staple and secured by a latch-hook or other suitable method.

In use the cart is loaded in the coal-yard and run to the point of delivery. The trough

T is then extended, the sections being locked together as has been described, and the cart backed up so that the end of section *c* enters the cellar or vault-hole. The gates *e e* are now opened one at a time, as the coal should be delivered from one division of the cart-body before the other is opened, and thus avoid the liability to overflow the chute *T*. The bed *A* being of proper height to give the chute *T* the necessary inclination, the coal will be quickly delivered into the cellar or vault without soiling the pavements.

By the use of the longitudinal partition *E*, the business of retailing coal by the half ton is greatly facilitated, as it permits one-half the load to be deposited, and the remaining portion to be transported to a different locality and unloaded. The construction of the chute in sections, as shown, permits the same to be rendered more portable and efficient. The fixed spout *C* being made the full width of the cart-body, the contingency of overflow of coal is obviated.

Having given a full, clear, and exact description of our invention and its manner of operation, and shown its particular merits, what we claim as new, of our invention, and desire to secure by Letters Patent of the United States, is—

The combination of the rule-jointed folding chute *T* with the locking-clamp *o*, fixed spout *C*, swinging doors *e e*, and inclined-bottom cart-body *A*, substantially as and for the purpose set forth.
